UNITED STATES PATENT OFFICE

2,096,123

VENTILATOR

James H. McDerment, Cleveland, Ohio, assignor
to The Swartwout Company, Cleveland, Ohio,
a corporation of Ohio

Application August 21, 1935, Serial No. 37,196

8 Claims. (CL. 98—42)

This invention relates to a ventilator and particularly to that general type of ventilator shown in United States Patent to Dexter No. 1,611,005.

Broadly stated, the object of the invention is to provide improved damper mounting and control mechanism. More specifically, an object is to provide a damper mounting including a parallelogram linkage and a damper actuator comprising a reciprocable element connected to the damper through a toggle linkage. A further object is to provide for mounting the damper on a parallelogram linkage in such manner that the damper may be swung by the above mentioned toggle linkage to a position above the pivot mounting of the upper ends of the links constituting the parallelogram linkage. A further object is to provide improved actuating means for the above mentioned sliding bar, such means embodying a compound mechanism including a winding drum and pulley system connected in operative relation whereby to multiply the mechanical advantage of the actuating mechanism and at the same time provide for straight-line movement of the slideable bar and for remote control from any desired position.

Other and more limited objects will become apparent from the following description when read in connection with the accompanying drawings wherein Fig. 1 is a vertical transverse section through a device embodying the invention, and corresponding substantially to the section on the line 1—1 of Fig. 3a; Fig. 2 is an enlarged detail section corresponding substantially to the line 2—2 of Fig. 3; Figs. 3 and 3a constitute a longitudinal vertical section through a sufficiently large portion of the device to indicate the essential mechanism, it being understood that the mechanisms of Fig. 3a may be repeated indefinitely, only one latch mechanism, however, being required for the entire length, no matter of what extent; Figs. 4 and 4a make up a horizontal section corresponding substantially to the line 4—4 of Fig. 1; Fig. 5 is a fragmentary vertical section showing a modified form of actuating mechanism; Fig. 6 is a fragmentary plan view thereof with portions broken away; Fig. 7 is a fragmentary vertical section of a further modified form; Fig. 8 is a detail section corresponding to the line 8—8 of Fig. 7; and Fig. 9 is a fragmentary detail section of a still further modified form, being confined to a substitute for that portion of the actuating mechanism appearing at the lower right hand corner of Fig. 7.

By reference to Fig. 1, it will be seen that my improved ventilator is applicable to, for example, a building roof indicated by the numeral 10 and

carrying upwardly converging sheet metal elements 11 having their upper edges secured together at intervals by bars 12 extending thereacross and riveted thereto as well as to bows 13 having lower portions lying along the elements 11 and vertically extending portions positioned adjacent the upper edges of the elements 11 and connected together by upper bight portions. The bight portion of the elements 13 merges with the legs thereof by flattened corners to which is secured a ridge roll 14. Upwardly and outwardly extending supporting bars 15 are secured to the bows 13 and provide supports for the upper edges of baffle elements 16 which are attached at their lower edges to the elements 13 in any suitable manner. As will be clear from Fig. 1, the elements 11 terminate in vertical portions 17 upon which the outer edges of a damper 18 are adapted to rest. Secured to the damper 18 and extending thereacross at intervals are straps 19 to the ends of which are pivotally connected links 20. The upper ends of the links 20 are pivoted to the bows 13, as indicated at 21. It will be noted that the points 21 are above the damper 18 when the same is closed but that the position of the links 20 outside the edges of the damper 18 effectively removes the said links from the path of the damper and permits the latter to swing to a point above the pivot points 21.

Referring now particularly to Figs. 3 and 3a and 4 and 4a, it will be seen that certain of the transverse members 12 are provided with brackets 22 forming guide means for a slidably mounted bar 23. Attached at the point 24 to the two sides of the bar 23 are straps 25 making up a toggle link which is connected by a suitable bracket 26 to the bottom of the damper 18. It will be obvious that, by reciprocating the sliding bar 23, the linkage 25 can be caused to move to the dotted line position indicated in Fig. 3a wherein the damper 18 is positioned above the pivot point 21.

In Figs. 2 to 4a I have shown a form of actuator for the sliding bar 23 which comprises a flexible element 27 connected at 28 to the bar 23 and extending tangentially to a sector-shaped element 29 and connected thereto as indicated at 30. It will be noted that the element 29 is fixedly secured to a lever 31 which is pivoted to a cross member 32 as indicated at 33. The sector-shaped element is provided with a groove 34 in which the cable 27 is adapted to be received for winding on such sector-shaped element. The lever 31 is provided with a sheave 35 about which a cable 36 extends, such cable being fixedly connected to a stationary bar 37 at the point 38 at which point is located a

pin serving not only as a connector for the cable 36 but also as mounting for a sheave 38 about which the cable 36 extends and from which it passes to another sheave 40 and thence downwardly to a convenient position.

A latch means is provided for holding the bar 23 in a position to cause the damper 18 to remain in open position. Such latch may take the form of a latch element 41 pivotally carried by a 10 mounting bracket 42 which is in turn carried by the bar 23 and a cooperating latch receiving and holding element 43 carried by some fixed part of the device as, for example, one of the transverse members 12. This latch is similar to 15 that shown in my copending application Serial No. 727,306, filed May 24, 1934, now Patent No. 2,072,461, patented March 2, 1937, and operates to latch upon motion of the bar 23 to bring the latch 41 and the latch receiving element 43 into 20 engagement and is disengaged by a further operation of the element 36 after the same has been released. Inasmuch as this latch mechanism does not per se form a part of this invention and has been fully described in my said copending 25 application, it appears unnecessary to describe the operation thereof in detail.

Referring now to Figs. 5 and 6 wherein similar reference numerals indicate those parts which are common to the form of the invention just 30 described and wherein the modified elements are indicated by other reference characters, it will be seen that the sliding bar 23 carries a sheave 44 over which passes a flexible element 45 which is secured at one end, at the point 46, to a transverse bar 47 and at the other end to a sprocket wheel 48 at the point 49. The element 45 is adapted to be wound on the shaft or drum 50 by rotation of the sprocket wheel 48 by means of a sprocket chain 51 extending downwardly to 40 a position for convenient access. The shaft 50 is journaled in suitable bearings 52 carried by longitudinally extending angles 53 connected in spaced relation to the transverse bar 47 and another parallel transverse bar 54.

45 Referring now to a further modified form of Figs. 7 and 8, it will be seen that the sliding bar 23 is actuated by means of a toggle link 55 connected thereto through the medium of a suitable bracket 56 and pivotally connected at its lower 50 end to an actuating and latching assembly indicated generally by the numeral 57. The assembly 57 is slidable on a rod 58 which is suitably mounted on any fixed element, for example, one of the elements 11 through the medium of a supporting post 59 and spacing brackets 60 and 61. The element 57 may take the form of a box-shaped element 62 having leaves 63 pivoted therein and urged outwardly by a spring 64. Secured to the element 62 is a projection 65 to which the link 55 is pivoted and through which extends the reduced portion 66 of a vertically extending operating rod 67. It will be obvious that a sufficient force supplied in either direction to the assembly 57 will move the same along the rod 58 and that it will automatically remain in any position to which it is set. When an upward force is applied to the rod 67 the lower leaf 63 will be pushed upwardly against the resistance of the spring 64 so that that leaf will be released from its frictional grip on the rod 58. The upper leaf 63 will then ride along the rod 58, frictionally engaging the same to some extent but not to a sufficiently great extent to materially 70 increase the force required to move the housing 75

62 upwardly against the resistance of the forces of reaction transmitted through the link 55.

In lieu of the elements 57, 58, 59, 60, I may employ a post 68 to which are secured spacing elements 70 provided with bearings journaled in a threaded element 71 upon which is received an internally threaded, sliding block 72 having a projection 73 to which is pivotally attached the link 55. The lower end of the element 71 may be provided with a crank and located any distance below the ventilator convenient for operation of the latter.

In describing the modified forms of the invention, I have described only the portions of the general construction which are different in that modification and it is to be understood that the remaining portions are the same or substantially the same as those of the form illustrated in Figs. 1 to 4.

While I have shown and described the present preferred embodiments of my invention, I wish it understood that I am not limited to the details of the disclosure but only in accordance with the spirit and scope of the appended claims.

Having thus described my invention, what I claim is:

1. In a ventilator, walls defining an opening, a damper adapted to close said opening, and means for moving said damper substantially parallel to said opening and itself, said means comprising supporting means carried by said walls, parallel links pivoted to said supporting means and to said damper, a bar slidable with respect to said supporting means, link means connecting said damper and said bar, means for reciprocating said bar and latch means for releasably holding said bar to retain said damper in one position.

2. In a ventilator, an opening, a damper adapted to close said opening, supporting means, a parallelogram linkage pivotally connecting said damper to said supporting means, said linkage being positioned out of the path of said damper whereby the latter may swing from a position below the point of connection of said linkage to 45 said support to a position thereabove, a sliding bar mounted for reciprocation, additional link means pivotally connecting said sliding bar in operating relation to said damper, and means for reciprocating said sliding bar to move said damper from a position below the pivot connection of said linkage to said supporting means to a position thereabove.

3. In a ventilator, in combination with means defining an opening, a damper adapted to close said opening, a supporting means fixed adjacent said opening at opposite sides thereof, a parallelogram linkage connecting said damper with said supporting means, said linkage being pivotally connected to said supporting means at points above said damper and at points similarly longitudinally spaced from the points of connection of said linkage to said damper, the links constituting said linkage being positioned outside the outline of said damper and means for moving said damper from a position below the pivot connections of said linkage to said supports to a position thereabove.

4. In a ventilator, in combination with means defining an opening, a damper adapted to close 70 said opening, supporting means, a parallelogram linkage connecting said damper with said supporting means, a slidable bar mounted for reciprocation in a direction substantially parallel to said damper, a link connecting said sliding bar 75

in actuating relation to said damper, a flexible element connected to said sliding bar, a lever pivoted at a point fixed with respect to said first mentioned means, a sector-shaped drum carried by said lever and connected to said flexible element in relation to be wound thereon, a pulley system connected to said lever radially outwardly of said sector and adapted to actuate the same and latch means for holding said damper in one position.

5. In a ventilator, in combination with means defining an opening, a damper adapted to close said opening, supporting means, a parallelogram linkage connecting said damper with said supporting means, a slideable bar mounted for reciprocation in a direction substantially parallel to said damper, a link connecting said sliding bar in actuating relation to said damper, a flexible element connected to said sliding bar, a lever pivoted at a point fixed with respect to said first mentioned means, a sector-shaped drum carried by said lever and connected to said flexible element in relation to be wound thereon, a pulley system connected to said lever and adapted to 20 actuate the same and latch means for holding said damper in one position.

6. In a ventilator, in combination with a damper and means defining an opening adapted to be closed thereby, a parallelogram linkage mounting 30 said damper with respect to said opening, a bar mounted for sliding movement substantially parallel to said damper, a rod extending at substantially right angles to said bar, an actuating element movable longitudinally of said rod, a toggle

link connecting said actuating element with said bar and means for moving said actuating element longitudinally of said rod.

7. In a ventilator, in combination with a damper and means defining an opening adapted to be closed thereby, supports adjacent said opening, a parallelogram linkage pivotally connecting said supports with said damper, a sliding bar movable with respect to said damper, link means pivotally connecting said sliding bar and said damper, a flexible element, means connecting said element to said sliding bar, drum means mounted in fixed relation to said first means, said flexible element being secured to said drum means in relation to be wound thereon, means for causing 15 rotation of said drum means, and latch means for holding said damper in at least one position.

8. In a ventilator, in combination with a damper and means defining an opening adapted to be closed thereby, supports adjacent said opening, a parallelogram linkage lying outside the path of 20 said damper and pivotally connecting same to said supports, a sliding bar movable with respect to said damper, a link pivotally connecting said bar and said damper, a flexible element, means 25 connecting said element to said sliding bar in actuating relation thereto, drum means mounted in fixed relation to said first means, said flexible element being secured to said drum means in relation to be wound thereon, means for causing 30 rotation of said drum means, and latch means for holding said damper in at least one position.

JAMES H. McDERMINT.
